(57) **CLAIM**

The ornamental design for an agricultural vehicle with a fixed-height elevated platform, as shown and described.

DESCRIPTION

FIG. 1 is a perspective view of an agricultural vehicle with a fixed-height elevated platform showing our new design. FIG. 2 is a front elevation view of the agricultural vehicle with the fixed-height elevated platform of FIG. 1.

FIG. 3 is a rear elevation view of the agricultural vehicle with the fixed-height elevated platform of FIG. 1.

FIG. 4 is a left side elevation view of the agricultural vehicle with the fixed-height elevated platform of FIG. 1.

FIG. 5 is a right side elevation view of the agricultural vehicle with the fixed-height elevated platform of FIG. 1.

FIG. 6 is a top plan view of the agricultural vehicle with the fixed-height elevated platform of FIG. 1; and,

FIG. 7 is a bottom plan view of the agricultural vehicle with the fixed-height elevated platform of FIG. 1.

The dot-dot-dash lines in the drawings are included for the purpose of illustrating portions of the agricultural vehicle with the fixed-height elevated platform that form no part of the claimed design. The appearance of any portion of the agricultural vehicle with the fixed-height elevated platform between and including the dot-dash-dot lines form no part of the claimed design.
